UNITED STATES PATENT OFFICE

94,996

DESIGN FOR A SWINGING BACK FOR A BABY CARRIAGE

Donald W. Siebert, Gardner, Mass., assignor to
O. W. Siebert Company, Gardner, Mass., a cor-
poration of Massachusetts

Application December 17, 1934, Serial No. 54,444

Term of patent 14 years

To all whom it may concern:

Be it known that I, Donald W. Siebert, a citizen
of the United States, residing at Gardner, in the
county of Worcester and State of Massachusetts,
have invented a new, original, and ornamental
Design for a Swinging Back for a Baby Carriage,
of which the following is a specification, refer-
ence being had to the accompanying drawing,
forming part thereof.

Fig. 1 is a front elevational view of a swinging
back for a baby carriage showing my new design;
Fig. 2 is a side elevation thereof, and
Fig. 3 is a top plan view thereof.

I claim:

The ornamental design for a swinging back for
a baby carriage, as shown.

DONALD W. SIEBERT.
